UNITED STATES PATENT OFFICE.

WILLIAM L. R. EMMET, OF SCHENECTADY, NEW YORK, ASSIGNOR TO THE
GENERAL ELECTRIC COMPANY, A CORPORATION OF NEW YORK.

THERMAL CUT-OUT.

SPECIFICATION forming part of Letters Patent No. 769,598, dated September 6, 1904.

Application filed December 4, 1899. Serial No. 739,088. (No model.)

To all whom it may concern:

Be it known that I, WILLIAM LE ROY EMMET, a citizen of the United States, residing at Schenectady, county of Schenectady, State of New York, have invented certain new and useful Improvements in Thermal Cut-Outs, of which the following is a specification.

This invention relates to thermal interrupters or cut-outs for electric circuits, the object being to provide a device of this type which will safely interrupt circuits of high potential and large amperage.

My invention, although generally applicable to current-interrupters, is especially designed for use in shunt to circuit-breakers with currents of high potential and large amperage, in which the main circuit-terminals are first opened at the circuit-breaker contacts, the thermal device carrying the current for a sufficiently long period to permit a sparkless opening of the circuit at the main terminals and then giving way and extinguishing the arc, thus preventing damage to the circuit-breaker contacts or other supporting parts.

It is desirable to so design devices of this character that the fuses can be easily replaced.

I carry out my invention by mounting the fuse in a long plug containing a narrow opening with one or more enlargements of pockets at intervals in the length of the fuse, the plug being covered with a removable envelop, such as paper, and the whole adapted to be slipped into a support in which openings correspondingly located to the pocket or pockets are provided to permit the expulsion of the gaseous products due to the giving way of the fuse, over which opening or openings are placed chimneys to confine or give direction to the escaping vapors. The fuse may be a fine copper wire or strip which gives way almost instantly throughout its length and is vaporized, the gas escaping through the chimneys, its explosive force extinguishing the arc. Thus the only element damaged by the giving way of the fuse is the paper envelop, which can be readily renewed, permitting the cut-out to be used over and over again without deterioration. I provide a tube of insulating material—for example, wood—bored at appro-

priate distances for the vents above referred to and suitably supported so that the plug containing the fuse may be readily inserted and withdrawn. At the end of the insulating-tube are provided circuit-terminals with sockets and contacts for the fuse-terminals on the plug. Thus the examination of the fuse or the replacement of one which has been blown by a new one is a very easy matter.

The novel features of my invention will be more fully described hereinafter and will be definitely indicated in the claims.

In the accompanying drawings, which illustrate my invention, Figure 1 is a central sectional elevation through the insulation support of a cut-out embodying my improvements. Fig. 2 is a vertical transverse section on the plane indicated by the line *xx* of Fig. 1. Fig. 3 is an end view looking from the left of Fig. 1, showing the arrangement of the circuit-terminal for the socket into which the plug is inserted. Fig. 4 is a transverse section on a plane indicated by the line *yy* of Fig. 1. Fig. 5 is a sectional view of the plug at an intermediate point between the fuse-terminals.

75

1 represents a base or support provided with bolt-holes, as indicated in dotted lines, to enable it to be clamped to the switchboard or other suitable point where the device is to be used. It carries on its rear side two brackets 80 2 2^a, wide spaced at the point of connection with the support and coming together to hold a carrier for the insulating-tube at their lower ends. This carrier is formed of a plate of insulating material 3 and mounted on an insulating-tube bolted to the brackets by means of the caps and washers of insulating material and bolt, as indicated clearly in Fig. 2. A block of wood or other insulating material 4, centrally bored, is supported in sheet-metal 85 hands 5 5^a, bolted to the plate 3, and in order to strengthen the tube it may be wire wound, as indicated at 6 6^a. In the ends of the tube are lagged metal collars 7 7^a, acting as guides and contacts for the fuse, secured to 90 the plug by set-screws, as shown. Each collar carries a circuit-terminal 8 8^a, bored to 95 form a loose fit and split on the inside to per-

mit clamping over the tube by a set-screw 9. (See Fig. 3.) The circuit-wires are set in a hole bored in the side of the terminal where it is locked by set-screws 10. The fuse-plug 5 may be made of wood and provided with a narrow longitudinal groove, such as 11, Fig. 2. In the ends of this groove are inserted sheet-metal strips 12 12^a, riveted to a metal sleeve 13 13^a, fastened to the plug at suitable 10 distances to engage the sockets 7 7^a. To these plates the fuse 14 may be fastened by set-screws or any other convenient engaging device. Thus when the fuse is in place in the plug it lies snugly in the groove 11. At intervals in the length of the slot are enlargements or pockets 15 15^a, &c., opposite which vents 16 16^a 16^b are formed in the insulating-support. These pockets are somewhat wider and deeper than the fuse-groove, thereby permitting 20 the part of the fuse which extends through the pocket to be entirely surrounded by a gas or air medium and permitting a rapid rise of heat at this point when the fuse is overloaded relatively to the other parts of the fuse, 25 which are in contact with the walls of the groove and which therefore heat much more slowly, the result being that the fuse gives way first at the pocket and fusion quickly extends toward the terminals in both directions. 30 Around these vents are mounted chimneys 17 17^a, fixed in countersunk annular holes bored in the support. The end terminal of the support carries a spring 18, the end of which is adapted to snap into a slot cut transversely in the socket 35 7, thus acting to force the metal collar 13, connected with the fuse-terminal, into good contact with the socket. Connection at the inner end may be effected by means of a wire spring 19, mounted on the plug and projecting 40 through a slot in the terminal collar, the spring being provided with a curved engaging face, so as to permit insertion and withdrawal of the plug. In order to insure proper alignment of the plug in inserting it in the 45 support and permit the springs to fall into their seats, I employ a guide, which may be of any desired character; but the type shown is cheap and effective, comprising a slot in the plug-handle 20, which may be pushed home 50 in its seat when in alignment with a projecting pin 21, fastened to the support 1. Thus in connecting the cut-out into circuit the only act necessary is to insert the plug in its socket and push it home. 55 In order to prevent a distribution of the hot gaseous products of the arc along the plug, I provide a removable covering for the pockets 15 15^a, &c., for which I preferably employ paper, (see Fig. 5,) which may be wound 60 around or be employed in the form of a tube and pushed over the plug. The paper tube may be provided with holes opposite the pockets and chimneys, as indicated. The tube acts as a gas-check, preventing the hot vapors being distributed over the inner wall of tube 4. 65

When the fuse blows, it melts first at the pockets and instantly spreads along the groove, the gases are driven forcibly out through the support and chimneys, and the arc extinguished.

What I claim as new, and desire to secure by Letters Patent of the United States, is—

1. A fuse comprising a wire, a grooved support in which the wire rests and against which it bears throughout the major part of its length, and one or more enlargements of the groove 75 leaving a free air-space all around the wire at a point or points desired to first give way, the said wire being in contact with the grooved walls at all other points.

2. A cut-out comprising a socket provided with circuit-terminals at front and rear and one or more vents in the socket-walls between said terminals, and a plug connection adapted to be inserted and withdrawn quickly from the socket. 80

3. A thermal cut-out for electric circuits, comprising a socket containing elastic circuit-terminals at front and rear and provided with one or more long vents intermediate its ends, and a removable plug carrying a fuse adapted 90 when the plug is inserted to automatically engage the terminals and extending across the vent or vents.

4. A thermal cut-out comprising a socket, a plug carrying a fuse adapted to be quickly introduced into and withdrawn from said socket, elastic circuit-terminals at the front and rear of the socket completed when the plug is inserted, one or more vents in the walls of the socket, and corresponding gas-pockets in the 100 plug. 95

5. A cut-out comprising a socket provided with circuit-terminals, one or more vents in its walls, a plug carrying a fuse adapted to connect electrically with the terminals when inserted in the socket, said fuse extending transversely of the vent or vents, and a thin removable lining for the socket. 105

6. A cut-out comprising a socket provided with circuit-terminals, one or more vents in its walls, a plug carrying a fuse adapted to connect electrically with the terminals when inserted in the socket, said fuse extending transversely of the vent or vents, and a removable tubular septum between the plug and socket. 110 115

7. A thermal cut-out comprising a socket, a plug carrying a fuse adapted to be inserted into and withdrawn therefrom, circuit-terminals mounted on the socket adapted to be engaged by the fuse-terminals when the plug is inserted, one or more gas-pockets in the plug along the fuse, a paper tube carried by the plug, and vents in the socket corresponding to the pockets. 120

8. A thermal cut-out comprising a tubular support, a plug carrying a fuse adapted to be inserted into and withdrawn therefrom, circuit-terminals completed when the plug is inserted, and metal strengthening-bands on the insulating-support. 125 130

9. A thermal cut-out comprising an insulated tubular support, a plug adapted to be inserted into and withdrawn therefrom, circuit- terminals connected when the plug is inserted, 5 a fuse mounted on the plug, one or more vents for the gaseous products, when the fuse blows, and chimneys for said vents.
10. A thermal cut-out comprising a tubular support, a plug carrying a fuse adapted to be inserted into and withdrawn therefrom, circuit connections completed when the plug is inserted, a fuse mounted on the plug, vents in the support opposite the fuse, and a guide for insuring alinement of the fuse with relation 15 to the vents when the plug is inserted.
11. A thermal cut-out comprising a socket of insulating material provided with vents in its walls, a fuse-carrying plug adapted to be inserted in the socket, tubular terminals on the socket and plug, and springs to hold them 20 in firm engagement when the plug is inserted.
12. A thermal cut-out comprising a support, brackets behind the same, an insulated socket mounted thereon, circuit - terminals on the socket, and a fuse-carrying plug adapted to 25 be inserted in the socket from the front of the support.

In witness whereof I have hereunto set my hand this 2d day of December, 1899.

WILLIAM L. R. EMMET.
